(57) **CLAIM**

The ornamental design for a wire shelf, as shown and described.

DESCRIPTION

FIG. 1 is a front perspective view of the wire shelf, showing our new design;

FIG. 2 is an enlarged top plan view;

FIG. 3 is an enlarged bottom plan view;

FIG. 4 is an enlarged side elevation view, (the view of the side opposite that shown in FIG. 4 is identical to that of FIG. 4);

FIG. 5 is a further enlarged front elevation view; and, FIG. 6 is a still further enlarged back elevation view.
